UNITED STATES PATENT OFFICE.

GEORGE ARTHUR GARDHAM, OF HIGHLAND PARK, MICHIGAN, ASSIGNOR OF ONE-HALF TO ARVIN C. WEBSTER, OF DETROIT, MICHIGAN.

STAMP AND METHOD OF FORMING THE SAME.

Application filed May 12, 1920. Serial No. 380,741.

To all whom it may concern:

Be it known that I, GEORGE A. GARDHAM, a citizen of the United States of America, residing at Highland Park, in the county of Wayne, and State of Michigan, have invented certain new and useful Improvements in Stamps and Methods of Forming the Same, of which the following is a specification, reference being had therein to the accompanying drawings.

The invention relates to stamps and the method of forming the same, and is particularly applicable to the engraving and embossing art in which the stamps or dies may be formed with raised patterns, letters, figures, etc. The invention has for one of its objects the provision of a stamp which has great strength and is durable. Another object resides in the method of rapidly forming the stamps and moreover by mechanical means instead of by manual operations. Further objects of the invention reside in advantageous features more fully herein-after set forth.

In the drawings:

Figure 1 is a front elevation of a machine for forming the stamp;

Figure 2 is a top plan view thereof, with the upper part of the machine omitted;

Figure 3 is a perspective view of a completed stamp.

1 is a vise comprising the interchangeable steel jaws 2 for holding the tool steel blank 3 during the heating and forming operations. This blank preferably has its outer face 4 located a substantial distance beyond the outer faces 5 of the jaws and furthermore, has the outwardly tapering end portion 6 leading from the main body portion 7 thereof to the outer face 4.

8 is an air hammer slidably mounted in the slide 9 upon the machine and 10 is a suitable matrix removably mounted in the air hammer. The arrangement is such that the matrix is positioned so that upon the sliding movement of the air hammer toward the vise 1, the matrix will engage the outer face 4 of the blank 3. 11 is a suitable foot lever for controlling the movement of the air hammer 8.

In operation the blank 3 is clamped between the jaws 2 of the vise 1 with its outer face 4 adapted to be engaged by the matrix

10. Upon actuating the foot lever 11, the air hammer 8 will be moved toward the jaws 5 2, and the matrix 10 mounted in the air hammer will strike a succession of blows upon the outer face 4 of the blank. Due to the fact that there is this succession of blows by the matrix against the blank, the characters, such as letters, figures, etc., formed upon the blank are clearly defined and require substantially no hand work to place the formed blank in condition to be used as a stamp.

For the purpose of forming a better and more durable stamp, the blank is heated before being operated upon by the matrix. In detail 12 are heating terminals upon opposite sides of the blank 3 and adapted to engage the opposite sides of the main body portion 7 of the blank. 13 are heating terminal control levers to which the heating terminals 12 are secured. These control levers are pivotally mounted at 14 upon the 75 machine and are adapted to be swung inward toward each other to bring the heating terminals into firm engagement with the blank 3. 15 is a transformer comprising the primary circuit 16 and the secondary circuit 80 17 which secondary circuit is electrically connected to the heating terminals 12. 18 is a housing for a control lever switch to the circuit breaker preferably mounted upon one of the heating terminal control levers 13. 85 19 is a suitable housing containing a switch and fuses for connecting the power feed line 20 to the primary circuit 16 of the transformer through the circuit breaker control switch in the housing 18. This switch is 90 suitably actuated from the rock arm 21 pivoted upon the same control lever as the housing 18 is mounted upon and having arm extending adjacent to the handle portion 22 of the control lever whereby the operator may 95 move the control levers toward each other to bring the heating terminals 12 into engagement with the blank 3 and then readily connect the transformer to the power feed line through the circuit breaker control 100 switch.

After the blank has been heated to the desired temperature, the transformer is disconnected from the power feed line by actuating the circuit breaker switch, and the 105 control levers are moved outwardly away

from each other to remove the heating terminals from engagement with the blank. The foot lever 11 is then actuated and the matrix 10 strikes a rapid succession of blows 5 upon the heated outer face 4 of the blank.

Since the blank has the outwardly tapering end portion 6, the temperature of the outer face 4 of the blank will be maintained for a long time so that the forming operation 10 can completely take place while the outer face of the blank is hot.

With the above method, the highly repetitive succession of light blows of the matrix caused by the air hammer imparts a 15 face impact to the blank, thereby insuring surface flow or forging of the blank to the exact sharpness of detail of the matrix being used. This exact sharpness of detail cannot be secured by a slow steady pressure 20 of a matrix unless the blank is heated and is completely confined in a supporting guide. Furthermore, this latter method is not as

practical and as good results cannot be secured as by my above described method.

What I claim as my invention is: 25

1. The method of forming a stamp, comprising the clamping of a blank at a substantial distance from one of its faces, the heating of the blank adjacent to its clamping means and the subjecting of said face of the 30 blank to a succession of blows by a matrix, while said face is heated.

2. The method of forming a stamp, comprising the subjecting of a blank to a rapid repetitive succession of light blows by a 35 matrix.

3. The method of forming a stamp consisting of clamping a blank at one end thereof, heating the free end of said blank and subjecting the heated free end of said blank 40 to a rapid succession of light blows from the matrix of an air hammer.

In testimony whereof I affix my signature.
GEORGE ARTHUR GARDHAM.
